TABLE

Charles J. Miller, Chicago, Ill.

Application July 25, 1932, Serial No. 624,441

5 Claims. (Cl. 45—116)

This invention relates to tables and it has for its object to support a drop leaf rigidly in raised position.

Another object of the invention is to utilize two of the table legs for supporting the drop leaf by moving these legs from their position beneath the table top to position beneath the drop leaf when the latter is raised and holding them rigidly in their extended position to form a firm and substantial support for the drop leaf.

And a further object of the invention is to provide novel means for guiding the legs in their movement to and from drop leaf supporting position and to hold them rigidly in any position to which they are adjusted.

In the accompanying drawings I have illustrated selected embodiments of the invention and referring thereto

Fig. 1 is a bottom plan view, partly in section, of a table top showing one drop leaf in lowered position and one drop leaf in raised position.

Fig. 2 is a sectional view on the line 2—2 of Fig. 1.

Fig. 3 is a detail perspective view partly in section.

Fig. 4 is a sectional view on the line 4—4 of Fig. 1.

Fig. 5 is a perspective view of a secretarial type of table embodying the invention.

Fig. 6 is a bottom plan view of one end portion of the table shown in Fig. 5.

Fig. 7 is a sectional view on the line 7—7 of Fig. 6, and

Fig. 8 is a detail perspective view, partly in section, of the construction shown in Figs. 5—7.

Referring to the drawings, 9 is the table top and 10, 10 are drop leaves secured to the table top by hinges 11. Four legs 12 are secured to the outer end of swinging arms 13 which are pivoted at 14 to the under side of the table top in pairs, each pair being located close to the edge of the table top and the arms of each pair being located close together. When the arms are positioned beneath the table top the legs will

be located close to the adjacent corners as shown at the right in Fig. 1, and when the arms are swung outward beneath the drop leaf they will extend angularly with relation to each other to a position near to the outer corners of the leaf, as shown at the left in Fig. 1. Each arm carries a segmental guide 15 which is rigidly secured thereto and projects from one side thereof to interengage a segmental guide 16 on the under side of the table top. These guides are prefer-

ably stepped to interengage as shown in Figs. 1 and 3 and both sets of guides are segmental and described on substantially the same arcs. The guides 16 are preferably undercut as shown at 16', Fig. 3, so that the projecting flange 15' on the guide 15 will ride in the undercut 16' between the table top 9 and the flange 16'' of the guides 16. The guides 16 are conveniently but not necessarily formed on the ends of strip 17 secured to the under side of the top board adjacent opposite edges thereof and the guides 15 are secured in mortises 18 in the upper edges of the arms 13, the arms being secured to the legs above the upper ends of the legs and the guides 15 being arranged to slide in contact with or closely adjacent to the under side of the drop leaf 10.

In the construction of Figs. 6—8 each arm 13' is secured to the leg 12 at the top thereof and is provided with a wide mortise 18'. The guide 15 is secured in the mortise and sufficient space is left to receive the end of the guide 16 when the arm is swung inward beneath the table top. In this construction the arm 13' is pivoted at 19 in a recess 20 between the table top and a strip 21 which is fastened to the under side of the table top, Fig. 8. In this construction the arm as well as the top of the leg contacts with the under side of the table top and the drop leaf whereas in the construction of Figs. 1—3 the arm does not contact directly with the table top of the drop leaf.

The table top of Fig. 1 may be provided with aprons 22 or other suitable frame devices if desired but they are not necessary to my invention. When the parts are in position with a drop leaf lowered it will hang freely by the hinges 11 from the edge of the table top and the arms 13 will be arranged in substantially parallel position with the drop leaf and oppositely directed so that the legs will be positioned close to the adjacent corners of the table top and thereby afford a substantial support for the table top, as shown at the left of Fig. 1. When the leaf 10 is raised the adjacent legs are swung outward, the movement being limited by stops 23 fastened to the under side of the drop leaf. These stops may be provided with projections 24 to engage between the arm 13 and the guide 15, Fig. 4, and thereby adding to the rigidity of the support for the drop leaf. Or the stops may be made with enlarged heads 25, Figs. 6—7, and the guides 15 may be projected at 26 beyond the arms 13' to engage these stops between the heads thereof and the drop leaf to add to the rigidity of the support for the drop leaf as in the construction of Figs. 1—4.

110

The table of Figs. 5-8 has a top 27 to receive a cabinet 28 and one leaf 29 is folded up and secured in upright position against the back of the cabinet by snap fasteners 30 while the other leaf 31 is adapted to be folded down and the legs extended to support it to form a desk. The space 32 may be utilized to store a typewriter machine. The cabinet may be made in any form or for any purpose desired. In this embodiment of the invention the leaves are preferably secured pivotally to the edges of the table top by side hinges 33. The cabinet may be removed bodily from the table so that the table may be used for other purposes. The invention is particularly adapted for using a table in the manner just described because the legs form a substantial support for the leaf 31 to hold it rigid and thereby make it suitable for pen writing or for typewriting.

I do not limit the invention to the particular embodiments herein shown and described but reserve the right to embody the invention in any form and in any tables for which it is or may be adapted within the scope of the following claims.

I claim:

25. 1. A table comprising a top, a drop leaf hinged to the top, guide means on the under side of said top, a pair of arms pivoted at one end to the guide means, legs carried by said arms at their other end, the pivots of said arms being located 30 in adjacent relation and adjacent an edge of the top so that the arms will project oppositely beneath the top and substantially parallel with the edge thereof to position the legs at the corners of the top, the guide means on the under side of 35 the top including undercut portions, and guide means carried by said arms and including flanges interengaged in the undercut portions on the guide means on the top to maintain the legs in rigid adjusted position beneath the top or beneath the drop leaf.

40. 2. A table comprising a top, a drop leaf hinged to the top adjacent one edge thereof, a pair of arms pivoted at one end to the top, legs carried by said arms at their other end, guides on the 45 under side of the top adjacent said edge thereof, guides carried by said arms and interengaged with the guides on the top to maintain the legs in rigid adjusted position beneath the top or beneath the drop leaf, said arms being oppositely

directed and substantially parallel with said edge of the top when the legs are arranged beneath the top and said arms being angularly disposed when the legs are arranged beneath the drop leaf, and said guides being registered when the legs are beneath the top and the guides on the arms overlapping the joint between the drop leaf and the top and engaged with the guides on the top when the legs are arranged beneath the drop leaf. 80

3. A table comprising a top, a drop leaf hinged to the top, a pair of arms pivoted at one end to the top, legs carried by said arms at their other end, guides on the under side of the top and including flanges spaced from said top, and guides carried by said arms and including flanges interposed between the flanges on the first-named guides and the top and movable relative thereto to maintain the legs in rigid adjusted position beneath the top or beneath the drop leaf. 85

4. A table comprising a top, a drop leaf hinged to the top, a pair of arms pivoted at one end to the top, legs carried by said arms at their other end, guides on the under side of the top and including flanges spaced from said top, guides carried by said arms and including flanges interposed between the flanges on the first-named guides and the top and movable relative thereto to maintain the legs in rigid adjusted position beneath the top or beneath the drop leaf, and stops on the drop leaf interengaged with the 105 guides on the arms when the legs are arranged beneath the drop leaf to limit the outward pivotal movement of the arms and to assist in maintaining the drop leaf in rigid position. 100

5. A table comprising a top, a drop leaf hinged to the top, guide means on the under side of the top and including undercut portions, a pair of arms each having one end thereof interposed in an undercut portion of said guide means, means pivotally connecting said ends of said arms to 115 said guide means, legs carried by said arms at their outer ends, said guide means having undercut portions, and guide means carried by said arms and including flanges interengaged in the undercut portions on the guide means on the top 120 to maintain the legs in rigid adjusted position beneath the top or beneath the drop leaf. 110
